UNITED STATES PATENT OFFICE.

NOBLE W. WOOD, OF BROOKLYN, NEW YORK.

AIR-LIFT FOOT-PIECE.

1,150,651.

Specification of Letters Patent. Patented Aug. 17, 1915.

Application filed April 17, 1914. Serial No. 832,600.

To all whom it may concern:

Be it known that I, NOBLE W. WOOD, a citizen of the United States of America, residing at Brooklyn, in the county of Kings and State of New York, have invented certain new and useful Improvements in Air-Lift Foot-Pieces, of which the following is a specification.

This invention relates to foot pieces for 10 that type of pumping apparatus commonly known as air lifts.

The object of the invention is to provide an improved article of this nature so constructed that it may be readily adapted for 15 use in connection with the types of air lifts already on the market.

A further object of the invention is the provision of an article of the nature set forth so constructed that obstruction of the flow 20 both of water and of foreign materials, is avoided and a quick formation of the air bubble is secured, whereby the efficiency of the apparatus is markedly increased.

Further objects and advantages of the invention will be set forth in the detailed description which now follows.

In the accompanying drawing, Figures 1 and 2 are vertical sectional views illustrating the principal forms of air lifts at present 30 upon the market.

Like numerals designate corresponding parts in both of the figures of the drawing.

The principal types of air lifts at present upon the market, are shown in Figs. 1 and 35 2. In Fig. 1 the air pipe is located outside of the water conducting pipe, and in Fig. 2 air flows downwardly through the annular space between the water conducting pipe and the casing and the water flows upwardly 40 through the centrally disposed water conducting pipe. It has been found in practice that when air is discharged into the water conducting pipe, as for instance that shown in Fig. 1, the bubbles take the form there illustrated. In many of the structures heretofore proposed the air has been discharged through a series of small openings disposed about the water or discharge pipe. After the air from a number of these openings has 50 collected so that a bubble is formed, the bubble starts to rise in the well known way. It is apparent that any structure which will cause these bubbles to form in the minimum space of time gives the greatest efficiency.

55 It is therefore the primary object of the present invention to provide as an article of

manufacture an integral footpiece adapted for connection with the types of water lifts already in use and which will introduce the air into the discharge pipe through unbroken 60 annular ports whereby, instead of the air being discharged into the column of water through a series of separate ports and then having to collect to form the bubble, the air is discharged in an unbroken steady stream, 65 immediately forming into bubbles and thereby greatly increasing the efficiency of the structure.

In carrying out the invention in conjunction with that form of air lift shown in 70 Fig. 1, wherein 5 designates the discharge or water pipe made up of the sections held together by the couplings 6, I provide as an integral casting with one of said sections a shell 7, having a boss 8 into which the air 75 pipe 9 may be threaded. The shell forms an air chamber 10 through the inner wall 11 of which I form an annular, unbroken port 12 which establishes communication between the air chamber 10 and the interior 80 of discharge pipe 5. Shell 7 therefore, not only serves the function of providing a wall for the air chamber 10 but it ties the two parts of the discharge pipe section above and below the annular port 12, together. It will 85 therefore be seen that I may place upon the market as an article of manufacture, a substitute for one of the sections of an ordinary discharge pipe and that when this substitute section is placed in position, the usual air 90 pipe 9 may be readily connected thereto with the result that an annular discharge of the air is secured whereby the highly advantageous results above set forth are achieved.

In the form of the device illustrated in 95 Fig. 2, 21 designates the well casing and 22 the discharge pipe. The discharge pipe section 24 and a tail pipe section 25 are united by the wall 26 constituting an air chamber. Ports 27 for the entrance of the air into 100 said chamber are provided, preferably in the top of said chamber, and the discharge pipe and tail pipe sections 24 and 25 have their ends spaced from each other enough 105 to constitute an annular port 27. In this form of the device the air flows downwardly between the discharge pipe and the casing through the port 27 and is discharged in an unbroken, steady stream through port 27 into the discharge pipe.

110 It is to be noted that there are several important advantages secured by this struc-

ture. The air is discharged into the discharge pipe in an unbroken stream whereby the quick formation of the air bubble is secured, together with an increased efficiency. 5 This is accomplished in every case with a foot piece which may be placed upon the market as an integral article of manufacture instead of having to be separately built up at the well, the foot piece being adapted for 10 ready connection with the pipe already in use. These important results are accomplished without impeding or obstructing the flow of the water or foreign material through the discharge pipe. It is frequently 15 the case that rocks of large size are discharged through these lift pumps, also large masses of clay frequently pass through them and it is of the utmost importance that the discharge pipe be so constructed as to prevent the jamming of these rocks in the discharge pipe which would necessitate pulling the apparatus from the well at considerable 20 trouble and expense.

From the foregoing description, it will be 25 seen that simple and efficient means are herein provided for accomplishing the objects of the invention, but while the elements shown and described are well adapted to

serve the purposes for which they are intended, it is to be understood that the invention is not limited to the precise construction set forth, but includes within its purview such changes as may be made within the scope of the appended claim. 30

Having described my invention, what I 35 claim is:

In a device of the character described the combination with the discharge pipe of a water lift, said pipe being provided with a narrow unbroken annular port, of an air 40 chamber surrounding said discharge pipe at the part thereof in which said port is formed the walls of said air chamber serving to tie together the parts of the discharge pipe separated by said annular port, said air chamber extending a material distance 45 above and below said port and means for introducing air under pressure to said chamber at a point out of alignment with said port. 50

In testimony whereof I affix my signature in presence of two witnesses.

NOBLE W. WOOD.
